DETACHABLY MOUNTED EYE STRUCTURE FOR DOLLS

Filed April 8, 1932

UNITED STATES PATENT OFFICE

DAVID ZAIDEN, OF BROOKLYN, NEW YORK, ASSIGNOR OF ONE-FOURTH TO ISAAC KAUFMAN, ONE-FOURTH TO SAMUEL KAUFMAN, BOTH OF FOREST HILLS, NEW YORK, AND ONE-FOURTH TO JACOB KAUFMAN, OF BROOKLYN, NEW YORK

DETACHABLY MOUNTED EYE STRUCTURE FOR DOLLS

Application filed April 8, 1932. Serial No. 603,948.

This invention relates to improvements in movable eye structures for doll heads, and to novel supporting means therefor which is capable of being detachably locked in operative position within the interior of the doll head so as to resiliently dispose the eye elements in operative relation to the eye socket openings provided in the doll head wall.

This invention has for its principal object 10 to provide a simple and easily applied support for movable eye elements of doll eye structures, which is of such construction that it may be quickly and easily detachably interlocked with and in operative relation to a doll-head; and, furthermore, wherein the 15 number of parts comprising the same have been reduced to a minimum and at the same time also reduced to great simplicity of form.

Another object of this invention is to provide 20 a supporting structure adapted to yieldably hold the eye elements, comprising the eye-ball and eye-lid members, relative to the eye-socket openings of the doll-head, whereby the same will automatically and readily 25 adjust themselves to the latter in compensation of expansion or contraction of the doll-head material, or warping or other slight distortions to which the doll-head may be subjected.

Other objects of this invention, not at this 30 time more particularly enumerated, will be understood from the following detailed description of the same.

An illustrative embodiment of this invention 35 is shown in the accompanying drawing, in which:—

Fig. 1 is a vertical longitudinal section, in part, of a doll-head equipped with the novel form of movable eye structure according to this invention; Fig. 2 is a transverse section of the same, looking to the left in Fig. 1; Fig. 3 is a view similar to that of Fig. 1, but showing the method of inserting within and applying the eye-structure to 45 the doll-head; Fig. 4 is an enlarged face view

of the manipulatable locking element for securing the eye structure in operative relation to and within the doll-head; said view is being taken on line 4—4 in Fig. 3; Fig. 5 is a fragmentary transverse section, taken on line 50 5—5 in Fig. 1; Fig. 6 is an enlarged fragmentary sectional view, taken on line 6—6 in Fig. 1; and Fig. 7 is a sectional view, taken on line 7—7 in Fig. 6.

Similar characters of reference are employed in the above-described views to indicate corresponding parts.

Referring to the drawing, the reference character 10 indicates a doll-head of the usual hollow construction having a bottom opening 11 in its neck-portion 12. The doll-head may be made of any suitable material, such, for example, as a molded plastic material which becomes rigid when hardened. Formed in the doll-head are the usual eye-socket openings. Preferably molded as an integral part of the doll-head, within the neck portion thereof, is a boss 13 having a countersunk seat 14, in the opposite side walls of which are formed indented latch slots 15. Also preferably molded as an integral part of the doll-head, at and within the top thereof, is a boss 16 having a V-shaped notch 17 provided in its forward end.

The novel eye-structure, according to this invention, comprises an upright carrier plate 18, having a longitudinally adjustable foot-piece 19 extending from its lower end, and fixedly connected thereto by a slot and screw adjustment 20—21. Rotatably mounted on said foot-piece 19 is a latch 22 of turn-button form, the same having an axial socket 23 of rectangular cross-sectional shape, suitable to be engaged by a pin-wrench 24, whereby the latch 22 may be actuated. While I have shown the carrier plate 18 provided with the adjustable foot-piece 19 upon which the turn-button latch 22 is mounted, it will be obvious that the foot-piece 19 may be eliminated and the latch 22 carried by the lower end of the 80 85 90 95

carrier plate. The advantage of the adjustable foot-piece 19 is that, through adjustment thereof, the height of the carrier plate may be modified, whereby the location of the eye elements, supported by the latter, relative to the eye socket openings of the doll-head may be accurately determined and fitted to any variations which may occur in the formation of the doll-heads on the quantity production basis.

Suitably secured to the upper end portion of said carrier plate 18, as by retention lugs 25, is an upwardly extending and bowed spring arm 26. This spring arm is provided at its free end with an angular terminal portion 27 which is engaged in the notch 17 of the boss 16 with which the upper interior of the doll-head is provided. When thus engaged the spring arm 26 resiliently supports the upper end of the carrier plate 18 and the eye structures carried thereby, so as to yieldably relate the eye elements to the eye openings of the doll-head. As shown said spring arm 26 may be provided, if desired, with a helical loop 26' intermediate its ends, whereby its resiliency may be increased, although this is not absolutely essential.

The upper free end portion of said carrier plate 18 is of bifurcate formation to provide a pair of laterally spaced apart ears, which are bent to form rearwardly extending U-shaped bearing loops 28, having their open ends forwardly presented. Mounted in the bight of said bearing loops 28 is a cross arm 29. Secured to said cross-arm, by solder or any other suitable means of fastening, is a depending pendulum lever 30, at and to the lower end of which is secured a pendulum weight 31 of suitable form. Intermediate the cross arm 29 and the weight 31, said pendulum 30 is provided with oppositely extending transverse actuator arms 32, suitably secured thereto by solder or other mechanical fastening means.

Journalled upon each end of said cross arm 29 is a hollow spherical sector forming an eye-lid element 33, and having integral therewith, or suitably secured thereto at one side thereof, a downwardly extending lever arm 33'. Each lever arm 33' possesses a bifurcate free end portion to straddle and thus be operatively engaged by the respective actuator arms 32. To position each eye-lid element 33 in laterally adjusted fulcrumed position on the cross arm 29, and so as to laterally dispose the same in operative relation to an adjacent eye-socket opening of the doll-head, sleeves 34 are slidably engaged over and upon each end of the cross bar so as to be adjustable thereon, and so as to pass through the respective sides of the eye-lid elements 33, said sleeves having stop flanges 35 to engage the adjacent sides of the latter. Connected with each eye-lid element 33, so as to cooperate therewith, is an eye-ball ele-

ment 36 of any suitable form or style. The eye-ball elements 36 are preferably secured to the eye-lid elements 33 so as to move therewith, substantially for example, as disclosed in my co-pending application for United States Letters Patent, Ser. No. 594,437, filed February 23rd, 1932.

In order to supplement the resiliency of the spring arm 26, while at the same time permitting more or less independent rearward yielding of each eye device, the cross arm 29 is loosely mounted in the bearing loops 28 so as to be capable of forward and backward play therein, and so as to permit different degrees of corresponding movements of its opposite extremities, and a supplementary spring means is carried by the carrier plate 29 to exert a mild tensional forward thrust upon the cross arm, to thus yieldably hold the eye devices operatively related to the eye socket openings with which they are respectively associated. This supplementary spring means comprises a leaf spring, preferably of U-shape form as shown, the loop end 37 of which is anchored to the carrier plate by retention lugs 38, and the free ends of the arms 39 of which bear tensionally upon the rearward side of said cross arm 29.

In order to provide a stop to limit the eye device actuating swing of the pendulum lever 30, the lower fixed end of said spring arm 26 is angularly bent around the side of the carrier plate 18, with its free end again bent to extend across the back of the carrier plate in rearwardly off-set and spaced relation thereto so as to provide a stop-member 40 to arrest rearward or inward swinging movement of said pendulum lever 30.

To assemble the movable eye structure within and in operative relation to the doll-head, the turn-button latch 22 is initially turned with its long axis aligned longitudinally to the carrier plate, and the pin wrench 24 is engaged in the axial opening 23 of the turn-button latch. The structure is then inserted within the doll-head, so that the free upper end of the spring-arm 26 is engaged in the notch 17 of the boss 16. The lower portion of the carrier plate is then thrust forwardly and into the seat 14 of the boss 13; whereupon the turn-button latch 22 is rotated to carry its ends respectively into the latch slots 15, thus interlocking the mounting structure in operative position within the doll-head, and with the eye device thereof operatively related to the eye-socket openings of said doll-head. It will thus be obvious, that by this very simple and easily effected manipulation the eye structure may be quickly and yet detachably affixed to and within the interior of the doll-head; and when so affixed, the eye devices will be also resiliently or yieldably supported relative to the eye-socket 130

openings so as to readily adjust themselves operatively thereto.

When the movable eye-structure is affixed in place within the doll-head, in the manner above indicated, the operation of the eye devices will be controlled by the weighted pendulum lever 30, whereby as the latter swings rearwardly, which will occur when moving the doll-head from a vertical or upright position toward a horizontal or reclining position, the actuated arms 32 will transmit, through the lever arm 33', rotative movement to the eye-lid and eye-ball elements about the cross-arm 29 as an axis, thus causing the eye-lid elements to move downwardly across the eye-socket openings of the doll-head in closed relation thereto.

As many changes could be made in the above-described constructions, and many apparently widely different embodiments of the invention could be made without departing from the scope thereof, it is intended that all matter contained in the above description or shown in the accompanying drawing, shall be interpreted as illustrative and not in a limiting sense.

I claim:

1. The combination with a hollow doll-head having within its interior an upper boss and a lower boss, said lower boss having a countersunk seat provided in its side walls with latch slots, of a carrier plate having a resilient arm upwardly extending therefrom into engagement with said upper boss, a turn-button latch rotatably connected with the lower end portion of said carrier plate, said turn-button latch being movable to engage in said latch slots when said lower end portion of said carrier plate is seated in the seat of said lower boss, whereby said carrier plate and its resilient arm are secured in affixed operative relation to said doll-head, and pendulum actuated eye-devices supported by said carrier plate.

2. The combination with a hollow doll-head having within its interior an upper boss and a lower boss, said lower boss having a countersunk seat provided in its side walls with latch slots, of a carrier plate having a resilient arm upwardly extending therefrom into engagement with said upper boss, a turn-button latch rotatably connected with the lower end portion of said carrier plate, said turn-button latch being movable to engage in said latch slots when said lower end portion of said carrier plate is seated in the seat of said lower boss, whereby said carrier plate and its resilient arm are secured in affixed operative relation to said doll-head, U-shaped bearing means connected with the upper end of said carrier plate, a cross-arm supported in said bearing means, eye elements pivoted on said cross-arm, a weighted pendulum lever fulcrumed by said cross-arm, and cooperating means in connection with said pendulum lever

ver and eye-elements whereby the latter are actuated.

3. The combination with a hollow doll-head having within its interior an upper boss and a lower boss, said lower boss having a countersunk seat provided in its side walls with latch slots, of a carrier plate having a resilient arm upwardly extending therefrom into engagement with said upper boss, a turn-button latch rotatably connected with the lower end portion of said carrier plate, said turn-button latch being movable to engage in said latch slots when said lower end portion of said carrier plate is seated in the seat of said lower boss, whereby said carrier plate and its resilient arm are secured in affixed operative relation to said doll-head, U-shaped bearing means connected with the upper end of said carrier plate, a cross-arm supported in said bearing means, eye elements pivoted on said cross-arm, a weighted pendulum lever fulcrumed by said cross-arm, cooperating means in connection with said pendulum lever and eye-elements whereby the latter are actuated, and spring means anchored to said carrier plate to engage the rearward side of said cross arm at its intermediate portion to yieldably back the same.

4. The combination with a hollow doll-head having within its interior an upper boss and a lower boss, said lower boss having a countersunk seat provided in its side walls with latch slots, of a carrier plate having a resilient arm upwardly extending therefrom into engagement with said upper boss, a turn-button latch rotatably connected with the lower end portion of said carrier plate, said turn-button latch being movable to engage in said latch slots when said lower end portion of said carrier plate is seated in the seat of said lower boss, whereby said carrier plate and its resilient arm are secured in affixed operative relation to said doll-head, U-shaped bearing means connected with the upper end of said carrier plate, a cross-arm supported in said bearing means, eye elements pivoted on said cross-arm, a weighted pendulum lever fulcrumed by said cross-arm, each eye-element having a depending lever arm, and said pendulum lever having laterally extending actuator arms to respectively engage said eye element lever arms.

5. The combination with a hollow doll-head having within its interior an upper boss and a lower boss, said lower boss having a countersunk seat provided in its side walls with latch slots, of a carrier plate having a resilient arm upwardly extending therefrom into engagement with said upper boss, a turn-button latch rotatably connected with the lower end portion of said carrier plate, said turn-button latch being movable to engage in said latch slots when said lower end portion of said carrier plate is seated in the seat of said lower boss, whereby said carrier plate

plate and its resilient arm are secured in affixed operative relation to said doll-head, U-shaped bearing means connected with the upper end of said carrier plate, a cross-arm supported in said bearing means, eye elements pivoted on said cross-arm, a weighted pendulum lever fulcrumed by said cross-arm, each eye-element having a depending lever arm, said pendulum lever having laterally extending actuator arms to respectively engage said eye element lever arms, and spring means anchored to said carrier plate to engage the rearward side of said cross-arm at its intermediate portion to yieldably back the same.

15 6. The combination with a hollow doll-head having within its interior an upper boss and a lower boss, said lower boss having a countersunk seat provided in its side walls with latch slots, of a carrier plate having a resilient arm upwardly extending therefrom into engagement with said upper boss, a foot-piece adjustably connected with the lower end of said carrier plate for adjusting the effective height thereof, a turn-button latch 20 rotatably connected with said foot-piece, said turn-button latch being movable to engage in said latch slots when said foot-piece is seated in the seat of said lower boss, whereby said carrier plate and its resilient arm are secured in affixed operative relation to said doll-head, and pendulum actuated eye-devices supported by said carrier plate.

7. The combination with a hollow doll-head having within its interior an upper boss and a lower boss, said lower boss having a countersunk seat provided in its side walls with latch slots, of a carrier plate having a resilient arm upwardly extending therefrom into engagement with said upper boss, a foot-piece adjustably connected with the lower end of said carrier plate for adjusting the effective height thereof, a turn-button latch rotatably connected with said foot-piece, said turn-button latch being movable to engage in said latch slots when said foot-piece is seated in the seat of said lower boss, whereby said carrier plate and its resilient arm are secured in affixed operative relation to said doll-head, U-shaped bearing means connected with the upper end of said carrier plate, a cross-arm supported in said bearing means, eye elements pivoted on said cross-arm, a weighted pendulum lever fulcrumed by said cross-arm, and cooperating means in connection with said pendulum lever and eye-elements whereby the latter are actuated.

8. The combination with a hollow doll-head having within its interior an upper boss and a lower boss, said lower boss having a countersunk seat provided in its side walls with latch slots, of a carrier plate having a resilient arm upwardly extending therefrom into engagement with said upper boss, a foot-piece adjustably connected with the lower end of said carrier plate for adjusting the

effective height thereof, a turn-button latch rotatably connected with said foot-piece, said turn-button latch being movable to engage in said latch slots when said foot-piece is seated in the seat of said lower boss, whereby said carrier plate and its resilient arm are secured in affixed operative relation to said doll-head, U-shaped bearing means connected with the upper end of said carrier plate, a cross-arm supported in said bearing means, eye elements pivoted on said cross-arm, a weighted pendulum lever fulcrumed by said cross-arm, cooperating means in connection with said pendulum lever and eye-elements whereby the latter are actuated, and spring means anchored to said carrier plate to engage the rearward side of said cross-arm at its intermediate portion to yieldably back the same.

9. The combination with a hollow doll-head having within its interior an upper boss and a lower boss, said lower boss having a countersunk seat provided in its side walls with latch slots, of a carrier plate having a resilient arm upwardly extending therefrom into engagement with the upper boss, a foot-piece adjustably connected with the lower end of said carrier plate for adjusting the effective height thereof, a turn-button latch rotatably connected with said foot-piece, said turn-button latch being movable to engage in said latch slots when said foot-piece is seated in the seat of said lower boss, whereby said carrier plate and its resilient arm are secured in affixed operative relation to said doll-head, U-shaped bearing means connected with the upper end of said carrier plate, a cross-arm supported in said bearing means, eye elements pivoted on said cross-arm, a weighted pendulum lever fulcrumed by said cross-arm, each eye-element having a depending lever arm, and said pendulum lever having laterally extending actuator arms to respectively engage said eye element lever arms. 110

10. The combination with a hollow doll-head having within its interior an upper boss and a lower boss, said lower boss having a countersunk seat provided in its side walls with latch slots, of a carrier plate having a resilient arm upwardly extending therefrom into engagement with said upper boss, a foot-piece adjustably connected with the lower end of said carrier plate for adjusting the effective height thereof, a turn-button latch rotatably connected with said foot-piece, said turn-button latch being movable to engage in said latch slots when said foot-piece is seated in the seat of said lower boss, whereby said carrier plate and its resilient arm are secured in affixed operative relation to said doll-head, U-shaped bearing means connected with the upper end of said carrier plate, a cross-arm supported in said bearing means, eye elements pivoted on said cross-arm, a

weighted pendulum lever fulcrumed by said cross-arm, each eye-element having a depending lever arm, said pendulum lever having laterally extending actuator arms to respectively engage said eye element lever arms, and spring means anchored to said carrier plate to engage the rearward side of said cross arm at its intermediate portion to yieldably back the same.

10 In testimony, that I claim the invention set forth above I have hereunto set my hand this 6th day of April, 1932.

DAVID ZAIDEN.
